CAM

Gardell L. Bennett and Fredrick Dyer, Schenectady, N. Y., assignors to General Electric Company, a corporation of New York

Application April 3, 1942, Serial No. 437,538

2 Claims. (Cl. 74—568)

Our invention relates to cam operating means, more particularly to cam operating means for electric switches, and has for its object simple, reliable and inexpensive shockproof cam operating means.

In the operation of electric switches, a single cam against which a follower member is held by means of a spring has the disadvantage that it is not shockproof because of the fact that the spring is the operating means in one direction. For shockproof construction, two opposed cam faces, i. e., a cam slot, is required but such cams are costly, especially where a sequence of movements is required.

In carrying out our invention, we provide a plurality of cam sections having cam grooves in laterally different positions, which sections are interchangeable and may be assembled in desired relations to give the desired shape of cam slot.

For the movement of a switch member between closed and open circuit positions, we provide four different interchangeable cam sections, one for each position of the switch and one to effect movement of the switch in each direction.

More particularly, we provide one or more rotatably mounted operating members, each consisting of a disk sector provided with an arcuate slot on one side, which slot has for its center the axis of rotation of the disk. In this slot we assemble the interchangeable cam sections thereby to form a cam slot on one side of the disk sector of such shape as to give the desired sequence of operations.

Thus by suitably assembling the cam sections, the circuit controlling member can be operated from one position to another at any desired angular position of the disk sector and maintained in either its closed or open circuit position throughout a predetermined amount of angular movement of the disk sector.

For a more complete understanding of our invention, reference should be had to the accompanying drawings in which Fig. 1 is a side elevation view, partly in section, of an electric switch embodying our invention; Fig. 2 is a plan view, partly in section, of the device shown in Fig. 1; Fig. 3 is a partial sectional view along the line 3—3 of Fig. 2 looking in the direction of the arrows; Fig. 4 is a detail plan view showing the position ratchet means; Fig. 5 is a detail perspective view of an operating cam disk; while Fig. 6 is an exploded view in perspective of the stop means for the rotatable element.

Referring to the drawings, in carrying out our invention in one form we provide a square shaft

10 having its journal ends mounted in bearings 11 and 12 on the lower section 13 of an enclosing casing. One end of the shaft projects from bearing 12 and has secured to it an operating handle 14. Mounted on this square shaft 10 are a plurality of operating members 15 to 20, inclusive, shown as metal disk sectors. These sectors are mounted in pairs and the sectors of each pair are directly opposite each other in a common plane.

As shown in Fig. 5, each sector is provided with a square recess 21 at its center into which one side of the shaft 10 fits and with a transverse hole 22 which registers with a tapped hole 23 in the shaft. Thus the two disk sectors of a pair are placed on opposite sides of the shaft 10 with their holes 22 registering with the hole 23 after which each is secured separately to the shaft by a screw (not shown) engaging the tapped hole 23.

The sectors 15 to 20, inclusive, are identical in construction. Cooperating with them are identical switch structures only three of which, 24, 25 and 26, are shown. Each switch structure comprises a contact arm 27 (Fig. 1) having a stationary pivot 28 at its lower end and carrying a bridging contact 29 at its upper end. These contact arms are made of an electrically insulating material, preferably a molded compound such as a phenolic condensation product.

Each contact arm is provided with a follower member shown as a roller 30 secured to the contact arm on one side and having its axis of rotation parallel with the axis of the pivot 28. This roller extends into a cam slot 31, Fig. 5, in the side or face of the disk sector adjacent the contact arm whereby, when the handle is moved to turn the shaft and disk sector, the sides of the slot 31 on opposite sides of the roller 30 cause the roller to move radially with respect to the shaft in conformity with the shape of the slot whereby the contact arm 27 is moved between its closed and open circuit positions.

As shown in Fig. 2, the contact arms 27, 28 and 29 are situated on the cam slot sides of the sector 20, 18 and 16, respectively, with the operating roller 30 of each contact arm extending into the cam slot of its sector.

As shown in Fig. 5, each disk sector is provided with a relatively wide arcuate groove 32 on one side near its periphery, this groove having for its center the axis of rotation of the shaft 10. For the forming of the cam slot 31 a plurality of removable and interchangeable, radially extending, box cam sections 33 are mounted in this groove 32. For securing them in place each cam section has inner and outer grooves 34 and 35 across its

radially disposed ends, the groove 34, since it is on the radially inner end, being considerably narrower in its circumferential direction than the groove 35 on the outer end. On the opposite walls of the groove 32 are provided pairs 36, 37 of inner and outer projections or lugs which fit respectively into the grooves 34 and 35 when the cam sections are inserted in place in the groove 32.

To prevent the sections from slipping out, each is provided with a pin 38 on its inner side which extends through a hole 39 in the disk sector. On its outer end this pin is provided with a peripheral groove (not shown) forming a small shank over which is slipped a forked spring retaining member or clip 40. This clip 40 when it is inserted in place is compressed against the side of the disk sector thereby to hold the cam sections in place, and the prongs of the clip 40 are separated somewhat so that the clip is secured in place although it may be readily removed by a suitable tool, such as a screw driver.

In view of the fact that the switch arm 27 has only two positions, that is, a circuit closed position and a circuit open position, we have found that by providing four different cam sections 33, a cam slot 31 can be built up with the sections to give the desired movement of the contact arm at any desired angular position of the disk sector and maintain the contact arm in any desired position. Thus, referring to Fig. 5, it will be observed that four different sections are provided—an open circuit positional section 33a, a transfer section 33b which moves the switch arm from the open to the closed circuit position, an open circuit positional section 33c, and a transfer section 33d which moves the contact arm from the closed back to the open position.

These four cam sections 33a to 33d have the same overall size and construction so that they are interchangeable and have the same width of cam slot. They differ, as shown in the drawings, in the position of the slot adjacent one side or the other of the groove 32, i. e., as shown, in a radial direction, the positional sections 33a and 33c having, respectively, radially inner and outer slots, while the transfer sections 33b and 33d have radially or obliquely extended slots arranged to join the slots of the sections 33a and 33c for, respectively, radially outward or inward movement of the roller. Thus, the sections 33b and 33d are the ones that produce radial movement of the roller.

Considering the particular cam slot assembly shown in Fig. 5, beginning at the upper end, i. e., the counterclockwise extremity of the slot 31, it will be observed that the roller is in its radially innermost position and holds the switch arm in its open circuit position. As the disk sector is turned in a counterclockwise direction, the contact arm is moved by the third cam section to its closed circuit position where it is maintained over two cam sections. Then the contact arm is moved back to its open circuit position where it is maintained for four cam sections, after which it is moved to its closed circuit position, maintained there over one cam section, and then returned to its open circuit position over the next three remaining cam sections.

Preferably, the sectors 15 to 20, inclusive, and the cam sections 33 are die cast so that they do not require machining.

As shown in Fig. 1, the contact arm 27 is mounted on a metal supporting bracket 41 and this

bracket in turn is secured by a screw 42 to a cross supporting bar 43 secured to the bottom section 13 of the casing. The bracket 41 has a portion 44 extending upward above the cross bar 43 and to this portion is secured by a screw 45 a support 46 for the stationary contacts 47 and 48. This support 46 is also made of an electrically insulating material, preferably a molded material.

Thus, it will be observed that by removing the screw 42, the bracket 41 can be released from the cross bar 43 and each switch assembly removed as a unit. In order to secure the bracket 41 against turning about the screw 42, lugs 49 are provided on the lower end of each bracket which are in engagement with the cross bar when the screw is tightened.

In order to define the various angular positions of the shaft 10 for the desired switching positions, a metal disk sector 50, Figs. 2 and 4, is secured to the shaft with a separate sector 51 on the opposite sides of the shaft for indicating the open position only. These sectors 50 and 51 are secured to opposite sides of the shaft by means of separate screws, as shown. A spring pressed roller bears on the periphery of each of these sectors 50 and 51, only one roller 52 (Fig. 2) bearing on the sector 51 being shown in the drawings. This roller is mounted on the upper end of an arm 53 (Fig. 1) having a fixed pivot 54 on the casing and biased in a counterclockwise direction, as seen in Fig. 1, by a compression spring 55. An adjustable nut 56 is provided for the fixed end of the spring and by adjusting the position of this nut on its supporting bolt 57 the force applied by the spring can be adjusted as desired.

The two separate arm wheels 50 and 51 are provided in order that some particular position, such as the open position, for all of the contact arms can be designated to the operator as he moves the handle. Thus the sector 51 is provided with a single depression 58 for its roller 52, a corresponding depression 59 being provided on the other segment for its roller (not shown). When these two rollers are in these depressions, a much greater force is required on the part of the operator to turn the shaft and sectors to the next position in either direction. This increased holding force is an indication to him that the switch is in this particular position.

Furthermore, with the separate positioning rollers, the spring pressure of each can be adjusted independently. Preferably, the adjustment is such that a relatively light pressure is applied by the roller to the sector 50 whereas the roller applies a relatively great pressure to the sector 51. When the roller is out of the depression 58, however, it does not appreciably impede the rotation of the shaft because it bears on the remaining smooth arcuate surface of the sector 51.

In the switch disclosed, six operating sectors and six contact arms are shown for a multiplicity of control steps, for example, in the starting and control of an electric motor. Obviously, any suitable number of sectors and contact arms can be used to suit the requirements.

An adjustable limit stop means is also provided for limiting the arc through which the sectors can be turned. In view of the fact that each sector is slightly less than 180° in extent, the permissible rotation of the shaft 10 must be limited to less than 180° in any case. This is effected by stop projections 60 and 61 (Fig. 2) on the casing on opposite sides of the shaft 10 at the handle end. On the shaft adjacent the handle are two stop segment members 62 and 63

having projections 64 and 65 (Fig. 6) extending out far enough from the shaft to engage the stop 60 or 61. These members are provided with holes 66 and 67 through which a hub 67a on the handle extends loosely. Also, they are provided with 5 arcuate series of adjustment holes 68 and 69 through some registering two of which the screw 70 extends and is seated in a threaded aperture 71 in the lower end of the handle.

It will be observed that for the greatest possible amount of movement of the shaft 10, the two stop members 64 and 65 will be in registering relation. For a decreased amount of rotation, the members 62 and 63 are turned on the hub 67a with respect to each other so as to separate the projections 64 and 65 as desired, after which the screw 70 is inserted and the members clamped to the lower end of the handle.

The lower supporting part of the casing 13 is provided with an upper removable portion 72 carrying a gasket 73 to provide a sealed joint between the two.

While we have shown a particular embodiment of our invention, it will be understood, of course, that we do not wish to be limited thereto since many modifications may be made, and we therefore contemplate by the appended claims to cover any such modifications as fall within the true spirit and scope of our invention.

What we claim as new and desire to secure by Letters Patent of the United States is:

1. The combination with an operating shaft of means for turning said shaft, a disc member secured to said shaft and rotatable with said shaft, said disc member being provided with an arcuate groove on one side near its periphery having for its center the axis of said shaft, a plurality of pairs of interlocking means on the walls of said groove, the interlocking means of each pair being oppositely disposed from each other in a radial direction with respect to said disc member, a plurality of interchangeable cam sections mounted in said groove, each of said cam sections being provided with securing means at each end cooperating with one of a pair of said interlocking means whereby said cam sections are secured against movement along said groove, said cam sections having each substantially the same overall dimensions and being in side-by-side relation when mounted in said groove, each of said cam sections being provided with a cam slot having a predetermined radial width and said sections being arranged with said cam slots communicating with one another to form a continuous cam slot, there being sections having arcuate slots respectively adjacent their radially outer and inner ends and a cam section between said last mentioned sections having a connecting

transfer cam slots extending obliquely with respect to the radius of said disc member passing through said transfer cam slot so as to join together said arcuate cam slots, a movably mounted 5 driven member, and a follower member on said driven member lying in said continuous cam slot whereby upon rotation of said disc member said driven member is moved radially by the walls of said transfer cam slot between inner and outer positions, said follower member being locked by the walls of said arcuate cam slots in each of its inner and outer positions against movement radially in each direction.

2. The combination with an operating shaft 15 of means for turning said shaft, a disc member secured to said shaft and rotatable with said shaft, said disc member being provided with an arcuate groove on one side near its periphery having for its center the axis of said shaft, a 20 plurality of pairs of projections on the walls of said groove, the projections of each pair being oppositely disposed from each other in a radial direction with respect to said disc member, a plurality of interchangeable cam sections mounted 25 in said groove, each of said cam sections being provided with a slot at each end whose walls embrace one of a pair of said projections whereby said cam sections are secured against movement along said groove, means securing said cam sections 30 in said groove, said cam sections having each substantially the same overall dimensions and being in side-by-side relation when mounted in said groove, each of said cam sections being provided with a cam slot having a predetermined radial width and said sections being arranged 35 with said cam slots communicating with one another to form a continuous cam slot, there being sections having arcuate slots respectively adjacent their radially outer and inner ends to form 40 outer and inner arcuate cam slots having for their center the axis of said shaft and a cam section between said last mentioned sections having a connecting transfer cam slot extending obliquely with respect to the radius of said disc 45 member passing through said transfer cam slot so as to join together said outer and inner cam slots, a movably mounted driven member, and a roller on said driven member lying in said continuous cam slot whereby upon rotation of said disc member 50 said driven member is moved radially by the walls of said transfer cam slot between inner and outer positions, said roller being locked by the walls of said arcuate cam slots in each of its inner and outer positions against 55 movement radially in each direction.

GARDELL L. BENNETT.
